UNITED STATES PATENT OFFICE.

JOSEPH H. LYNCH, OF ASBURY PARK, NEW JERSEY.

CLASP.

1,369,823.

Specification of Letters Patent.

Patented Mar. 1, 1921.

Application filed April 26, 1920. Serial No. 376,470.

To all whom it may concern:

Be it known that I, JOSEPH H. LYNCH, a citizen of the United States, residing at Asbury Park, county of Monmouth, and State of New Jersey, have invented certain new and useful Improvements in Clasps, of which the following is a specification.

My invention relates to clasps, and particularly to clasps employed in laundries for the purpose of identifying the various articles of the laundry's customers. Clasps used for this purpose bear numbers or other identifying marks, are attached to the articles before putting them through the laundrying operations, accompany the articles through the laundrying operations, and are then used as a means of identifying the articles of the different customers.

Pins constricted more or less along the idea of the ordinary safety pin have been employed, and while they are fairly satisfactory when used in connection with coarse and rough articles, they nevertheless have the disadvantage that they often become disengaged from the articles in passing through the laundrying machinery, and for this reason when they are used the articles themselves are generally provided with an additional identifying means by being marked with ink. This latter is inefficient because it requires two operations. Furthermore, the pins are very unsatisfactory for use in connection with the finer articles, such as handkerchiefs, table linen, shirt waists, etc., for the pins must necessarily pierce the articles; and such articles, because of their nature, cannot well be marked with ink.

It will thus be seen that what is required to overcome the difficulties is a device which can be readily secured to and detached from the articles without piercing or otherwise mutilating them; which is unlikely to become accidentally detached from the articles; which is compact and will not be crushed by the mangles and other laundrying machinery; and which presents a smooth outer surface so that it will not readily catch on anything. The object of the invention is to provide such a device.

In the accompanying drawings, in which I have illustrated the preferred forms of my invention, and in which like reference numerals designate like parts,

Figure 1 is a plan view of my clasp in open position,

Fig. 2 is a plan view of it in closed or clasping position,

Fig. 3 is a side elevation of clasp in open position looking in as from the bottom of Fig. 1,

Fig. 4 is a section on the line 4—4 of Fig. 2,

Figs. 5 and 6 are plan views of the clasp actuating member and the spring clasping member respectively,

Fig. 7 is a sectional view of a modification of the construction of my device, taken on a line similar to that on which Fig. 4 is taken, and Fig. 8 is a plan view of the spring employed in Fig. 7.

Referring to Figs. 1 to 6 inclusive of the drawings, 10 indicates a fairly strong and rigid U-shaped body member, provided with the loop 11 by means of which the clasps 75 may be strung along a line or rod for convenience in handling and assorting. This loop may be formed as a part of body 10, or it may be attached thereto in any suitable manner. The body 10 is provided on a suitable portion thereof with a number or other mark (125) for the purpose of identification.

Located between the wings of the body 10 is a spring clasping member 12, shown in plan in Fig. 6; and which, as illustrated in Figs. 3 and 4, is rigidly secured at one end to the body 10 by means of rivets or pins 13. This spring member is so bent that its free end 12^a normally touches or approximately touches the interior surface of the body 90 member 10 on the wall opposite the wall to which its other end is secured. The material of the article to which it is desired to attach the clasp is inserted through the opening 14 between one side of body 10 and the spring 95 clasping member 12; and in order that the member 12 will securely clasp and hold the material when in closed position, it is provided with the blunt projections 15. These projections are arranged substantially in line with perforations 16 in body 10. They are blunt in order that they will not injure the material.

The spring or clasp actuating member 17, shown in plan view in Fig. 5, consists of a piece of metal having a bent-over portion 18, and provided with an extended portion 19 for convenience in opening the clasp. Member 17 is secured within the body 10 by means of pin 20 about which it is turnable. 110 When member 17 is turned about its axis 20 from open position illustrated in Fig. 3, to

closed position illustrated in Fig. 4, its upper surface engages the lower surface of spring 12, follows along such surface, and acts as a cam to force the free end of the 5 spring toward the interior wall of the body 10 to which the other end of the spring is secured by pins 13. Thus when material is inserted in opening 14 it will be tightly 10 pressed and held by the spring against an inner surface of U-shaped body 10. While I have shown the member 17 provided with the bent-over portion 18, it is obvious that instead of being made in this manner the member 17 may be made of a piece of metal 15 of sufficient thickness to perform its function of moving the free end of spring 12 without the necessity of being bent over.

In the modification of my invention shown in Figs. 7 and 8, the only change 20 from that shown in Figs. 1 to 6 inclusive is in the manner of securing the spring member 12 and the spring actuating member 17 to the body 10. In this form a single shouldered pin or rivet 21 is employed for 25 this purpose. The pin has the shoulder 22 which presses against the spring member 12 and holds the latter firmly against the body 10. The spring or clasp actuating member 17 is pivotally mounted on the thicker portion 30 of the pin. In such an arrangement the spring 12 has its inner edge 12^b so arranged as to abut against the body 10, in order to further prevent the spring from turning about the pin 21 as an axis.

35 It will be noted that I have devised a clasp which has a smooth outer surface and is quite compact, which will engage and securely hold the material to which it is attached without perforating or otherwise 40 mutilating the material, which has all the working parts confined within the main body member and which when in closed or clasping position is practically a solid piece.

I claim:—

45 1. In a clasp, a rigid U-shaped body member, a spring clasping member located within and secured to said body member, and a clasp actuating member pivotally secured to said body member and movable about an axis 50 perpendicular to the plane of the wings of said body member into a position substan-

tially completely between the wings to actuate the clasping member and hold it in clasping position.

2. In a clasp, a rigid U-shaped body member, a spring clasping member located within and secured to said body member, and a clasp actuating member pivotally secured to said body member and movable about an axis perpendicular to the plane of the wings 55 of said body member through one of the open sides of said body member into a position substantially completely between the wings to actuate said clasping member and hold it in clasping position. 60

3. In a clasp, a rigid U-shaped body member, a spring clasping member located within and having an end secured to said body member, and a clasp actuating member pivotally secured to said body member and movable about an axis perpendicular to the plane of the wings of said body member into a position substantially completely between the wings to engage the free end of the spring member and force it into clasping 70 position. 75

4. In a clasp, a rigid U-shaped body member, a spring clasping member located within said body member, a pin secured between the wings of said body member having a shoulder engaging and securing said clasping member to said body member, and a clasp actuating member pivoted to said pin and movable about it into a position substantially completely within said body member to actuate the clasping member and hold it in clasping position. 80 85

5. In a clasp, a rigid U-shaped body member, a spring clasping member located within and having one end secured to one of the 90 wings of the body member and the other end normally resting substantially against the other wing of said body member, and a clasp actuating member pivotally secured within said body member and movable 95 about an axis perpendicular to the plane of the wings of said body member to engage and force the free end of said clasping member toward the wing to which the other end is attached.

JOSEPH H. LYNCH.
